Chicago, Ill., jointly

Application June 27, 1935, Serial No. 28,710

6 Claims. (CL 237—2)

The invention relates generally to heaters and particularly to an apparatus for heating an automotive vehicle propelled by an internal combustion engine.

At the present time most heaters for automotive vehicles derive their heat from the jacket water of the motor or from the exhaust, and frequently the quantity of heat supplied in that manner is insufficient, particularly for heating large buses and airplanes.

It is a primary object of the invention, therefore, to provide a heating apparatus for automotive vehicles having an independent heat generating source so as not to be dependent upon either the jacket water or the exhaust of the motor.

Another object is to provide a heating apparatus having an independent heat generating source which employs the fuel used by the motor of the vehicle with which the apparatus is associated so as to obviate the necessity of a separate supply of fuel.

Yet another object is to provide a heating apparatus having a burner in which suction is utilized for drawing a combustible mixture into the burner and for withdrawing the products of combustion therefrom.

A further object is to provide a heating apparatus for automotive vehicles having a heat source independent of the motor but with a connection to the intake manifold of the motor for drawing combustible mixture into the heat source and for disposing of the products of combustion.

A further object is to provide a heating apparatus for automotive vehicles having manual means for controlling the initiation of operation of the apparatus, and automatic safety means for preventing initiation of operation and for arresting operation upon the existence of predetermined conditions.

It is a general object of the invention to provide a heating apparatus of novel and improved construction having control means for governing both the generation and the radiation of heat.

Other objects and advantages will become apparent from the following detailed description taken in connection with the accompanying drawing, in which:

Fig. 1 is a schematic view of a heating apparatus embodying the features of the invention, in which the apparatus is shown partly diagrammatically and partly in elevation or in section.

Fig. 2 is an end view of the motor in Fig. 1

showing the circuit interrupting means for the spark coil.

Although there is illustrated in the drawing and hereinafter described in detail a preferred embodiment of the invention, it is to be understood that this is for the purpose of illustrating the principles of the invention and that the invention is not limited to the particular form illustrated. The scope of the invention will be pointed out in the appended claims.

As shown herein for purposes of disclosure, the apparatus comprises a closed circulatory system which may be either of the hot water or steam type and is composed largely of a radiator 5, adapted to be located so as to discharge into the body of the vehicle, and a heating coil 6 adapted to be located exteriorly of the body preferably in the motor compartment. The number of turns in the coil 6 is determined by what capacity the heating apparatus is to have. The circulatory system is completed by a supply duct 7 leading from the top of the heating coil 6 to the radiator 5 and a return duct 8 leading from the radiator to the bottom of the heating coil. When the system is operated as a steam system, there is interposed in the return duct 8 between the radiator and the heating coil a tank 9 having radiating fins 9^a so that the tank functions as a condenser converting the steam to water which then flows by gravity into the lower turn of the coil 6 and thus assures circulation in the system. Should the system be used as a hot water system, the tank 9 may be adapted to function as an expansion tank. A bracket 10 supports the radiator 5 in horizontal position and is formed with a bushing 11 adapted to extend through the wall dividing the body of the vehicle from the motor compartment. The bushing 11 is threaded externally to receive a nut 12 by means of which the bracket is clamped to the wall. Both the supply duct 7 and the return duct 8 extend through the bushing so that the radiator may be conveniently installed, and when installed will present a neat appearance.

Means is provided herein for rendering the apparatus operable independently of the jacket water or the exhaust of the motor (not shown) propelling the vehicle with which the heating apparatus is associated. To that end an independent heat generating means is provided which here takes the form of a burner 15 enclosing the heating coil 6. This burner preferably employs the fuel used in the motor of the vehicle and to that end derives the fuel from

the same source. In the present instance the burner is shown connected by a conduit 16 near the bottom of a float bowl 17 of a carburetor 18. The float bowl 17 in turn is connected in well known manner by a conduit 18 to the fuel supply tank, not shown. Interposed in the conduit 16 is a fuel and air proportioning device 20 having a fuel passage 21 constituting in effect a part of the conduit 16 and an air passage 22 open to the atmosphere, and discharging into an enlarged portion 21' of the passage 21 where the air mixes with the fuel. The relative proportion of fuel and air drawn through the device is determined by a needle valve 23 which is adjusted to give a combustible mixture. A valve 24 located at the point of discharge of the conduit 16 into the burner 15 governs the supply of combustible mixture to the burner. It will be seen from the foregoing that this connection provides a constant level supply source for the burner.

Combustible mixture is induced to flow into the burner through the conduit 16 and the products of combustion conducted away from the burner by suction. Though a separate vacuum motor might be provided for that purpose, the suction of the motor is here relied upon and to that end a conduit 25 is connected to the intake manifold 26 of the motor. Combustion within the burner is initiated and sustained by a spark plug 27 connected by a lead 28 to a spark coil 29 from which it derives its energy. Preferably a window 30 is provided in the burner located just below the spark plug so that it may be determined readily whether combustion is taking place within the burner.

Aiding the discharge and circulation of heat from the radiator 5 is a fan 33 disposed above the radiator to create a circulation of air over the radiator. The fan is driven by an electric motor 34 deriving its energy from a battery 35. The motor circuit includes a lead 36 connected at one end to one terminal of the battery 35 and at the other end to a switch 37. A lead 38 connects the switch 37 to the movable contact 39 of a rheostat 40 which in turn is connected by lead 41 to one terminal of the motor. The other terminal of the motor is grounded through a lead 42 to complete the motor circuit through the customary ground lead 43 of the battery.

In addition to driving the fan the motor 34 serves to interrupt periodically the circuit leading to the spark coil 29 for the purpose of energizing the same. To that end the motor 34 has a cam 46 fixed on the end of its shaft 45, opposite the fan 33 (see Fig. 2). Also mounted on that end of the motor are a stationary contact 47 and a pivoted contact 48, the latter being urged into engagement with the stationary contact by means of a tension spring 49, and periodically forced out of engagement by the cam 46. Contact 48 is connected by a lead 51 to one terminal of the spark coil 29 which in turn is grounded by a lead 52. A condenser 53 is connected across the spark coil in the customary manner. The stationary contact 47 is connected by leads 55 and 56 to the lead 38 and thence through the switch 37 and lead 36 to the battery 35 to complete the circuit for the spark coil. An ammeter 57 is preferably connected between the battery and the lead 38 in the usual manner. As is evident from the foregoing the spark coil circuit and the motor circuit are in parallel, with the rheostat 40 affecting only the motor circuit.

Control means is provided for the apparatus

which is partially manual and partially automatic. It will be seen from the foregoing that the switch 37 is common both to the motor circuit and to the spark coil circuit so that both circuits will be simultaneously energized or de-energized upon actuation of the switch. Actuation of the switch 37 is by manual means which also functions to coordinate the opening and closing of the valve 24 with the energization and de-energization of the circuits by the switch 37. In the present instance this manual means is in the form of a rod 60 connected at one end to an arm 61 on the valve 24 and at the other end extends slidably through a sleeve 62 in the dash 63 of the motor vehicle. Near its dash end, the rod is provided with a pin 64 engaging a slotted link 65 actuating the switch 37. Thus it will be seen that when the valve 24 is closed the switch 37 will be open so that neither the motor 34 nor the spark coil 29 will be in operation, and that when the valve 24 is open both the motor 34 and the spark coil 29 will be energized so that combustion will be initiated in the burner and air will be circulated over the radiator 5. The switch 37 is so constructed that initial movement of the rod 60 to the left closes the switch so that it will be closed upon any partial opening of valve 24. The sleeve 62 in the dash 63 is rotatable relative to the dash and to the rod 60 and carries the arm 38 of the rheostat 40 for controlling the speed of the motor 34. In this manner a convenient and neat control means for the apparatus is provided.

Automatic means are provided for modifying the manual control and as safety devices. To that end a thermostat 66 is connected in the spark coil circuit intermediate the leads 55 and 56. This thermostat when open serves to prevent energization of the spark plug 27 and thus arrests combustion in the burner 15, but does not arrest the motor 34. The thermostat 66 may be located wherever desired and may be made responsive to any predetermined temperature. For purposes of illustration only it is here shown mounted on the upper end of the burner 15.

In order to prevent injury to the apparatus by excessive expansion of the fluid in the circulatory system, a bellows 68 is connected to the circulatory system so as to be responsive to the pressure within the system. The bellows 68 serves to close the valve 24 and open the switch 37 when the pressure within the circulatory system attains excessive values, and to that end is connected to the rod 60. This connection includes a crank 67 pivotally mounted at 68 and one arm of the crank has a pin and slot connection with the rod 60. The other arm of the crank 67 carries a pin 69 engaging in a slot 70 in the end of a link 71 connected to the movable end of the bellows 68. The pin 69 and slot 70 form a lost motion connection functioning to enable the valve 24 to be closed manually at any time and serving to close and to retain the valve closed against manual opening at a time when the pressure in the circulatory system is excessive.

Having described the heating apparatus, the operation thereof may be briefly summarized as follows: Having first adjusted the fuel and air proportioning device 20 so as to give a combustible mixture with the grade of fuel employed, the apparatus is started simply by pulling out the rod 60. Such movement of the rod would open the valve 24 so that the vacuum within the burner 15 created by the connection to the intake manifold would draw combustible mixture

into the burner. Simultaneously with the opening of the valve 24, switch 37 would be closed and thus complete the circuit to the motor 34 and to the spark coil 29 so that the spark plug 27 would be energized and combustion within the burner initiated. Depending upon the amount of heat required, the operator of the vehicle could manually vary the rate of combustion by manipulation of the valve 24 or could completely cut off combustion by moving the rod 60 inwardly the full distance. In this case the supply of combustible mixture, as well as operation of the motor 34 and the spark coil 29, would be arrested.

Assuming, however, that the apparatus is started as above described and the valve 24 set at a certain position and left in that position, with the thermostat 65 located as shown herein, should the burner temperature rise above a predetermined value the thermostat would open and break the circuit to the spark coil 29. This would render the spark plug 27 inoperative and thus would arrest combustion within the heater until the thermostat would again close, but such opening of the thermostat would not affect the operation of the motor 34 which would continue to circulate air over the radiator and in the body of the vehicle.

Should the pressure in the circulatory system become excessive, the bellows 66 would be expanded and through the crank 67 would shift the rod 60 inwardly depending upon the degree to which the pressure had risen. If the risk in pressure is small, the bellows would move the rod 60 a limited extent only so as merely to reduce the supply of combustible mixture to the burner. But should that fail to restore the pressure to normal, further expansion of the bellows 66 would completely close the valve 24 and would also open the switch 37 to stop the motor and de-energize the spark coil. With the bellows in this position the rod 60 could not be actuated manually to initiate operation of the apparatus so that the bellows acts as a safety device preventing starting the apparatus when to do so would be dangerous. Because of the lost motion connection between the link 71 and the crank 67, contraction of the bellows 66 to normal would not again start operation of the apparatus, but such operation could again be started only by willful act of the operator.

It will be seen from the foregoing that I have provided a unique heating apparatus for motor vehicles which is not dependent upon the heat of the motor jacket water or of the exhaust and which does not require provision of separate means for supplying the fuel and for disposing of the products of combustion. The apparatus is readily installed, is economical in operation and is readily controlled and regulated to produce any desired quantity of heat.

I claim as my invention:

1. An apparatus for heating an automotive vehicle having an internal combustion engine, comprising a circulatory system including a radiator and a heating coil, a burner for supplying heat to said circulatory system having a fuel supply connection and a connection with the intake manifold of the engine for drawing fuel into the burner and withdrawing the products of combustion therefrom, a valve for controlling the supply of combustible mixture to the heater, means for initiating and maintaining combustion within the heater, an electric motor-driven fan for circulating air past said radiator, a switch controlling both said electric motor and the com-

bustion initiating means, and a common means for simultaneously actuating said valve and said switch.

5 2. An apparatus for heating an automotive vehicle having an internal combustion engine, comprising a circulatory system including a radiator and a heating coil, a burner for supplying the heat to said circulatory system having a fuel supply connection and a connection to the intake manifold of the engine whereby when the engine is in operation fuel is drawn into the burner and the products of combustion withdrawn therefrom, a valve for controlling the supply of fuel to said burner, manual means for controlling said valve, and automatic pressure responsive means having a connection with said valve for closing the same and maintaining the same closed against manual opening when the pressure in the circulatory system exceeds a predetermined value.

10 3. In a heat generating device for a conveyance having an internal combustion engine, a substantially closed cylinder separate from the engine and having two compartments, one providing a combustion chamber and the other a fluid chamber, a carbureting device connected to the intake of the combustion chamber for supplying a combustible mixture thereto, a fuel supply pipe from the fuel supply of the engine to the carbureting device, means responsive to the pressure in said fluid chamber for controlling the rate of flow of fuel to said carbureting device to increase the rate of flow upon reduction of the pressure in said fluid chamber and vice versa, an exhaust pipe from the outlet of the combustion chamber to the intake manifold of the engine, a spark plug operatively mounted in the combustion chamber, a high tension coil, a circuit from a source of electricity to the coil, an interrupter in said circuit, and a high tension wire from the coil to the plug.

15 4. The combination with a motor vehicle having an internal combustion engine, of a substantially closed receptacle separate from the engine and comprising a combustion chamber, a fluid chamber operatively associated therewith, a carbureting device connected to the intake of the combustion chamber, a fuel supply pipe from the carbureting device to the fuel supply of the engine, an exhaust outlet from the combustion chamber to the intake manifold of the engine, a control valve for controlling the rate of fuel supply to the combustion chamber at a rate inverse with respect to the pressure in said fluid chamber, a passageway from the fluid chamber to the control valve, a sight opening in said combustion chamber, a spark plug mounted in said combustion chamber, a radiator, connections from the radiator to the fluid chamber, an electric fan for forcing air around the radiator, a circuit from a source of electricity to the fan, a high tension coil, a circuit from said source of electricity to the coil, an interrupter actuated by the fan motor arranged in the coil circuit, and a high tension wire from the coil to the spark plug.

20 5. For use in conjunction with an automobile having an internal combustion engine including an intake manifold and a carburetor, a combustion chamber having an inlet and an outlet, means connecting the outlet of said combustion chamber to the intake manifold of the engine to withdraw products of combustion from said combustion chamber, means connected to the carburetor for supplying a combustible mixture

of liquid fuel and air to said combustion chamber, a valve for controlling the flow of the combustible mixture into said combustion chamber, electrical means for igniting the fuel mixture in said combustion chamber, an energizing circuit for said igniting means, said circuit including a switch, a manually operable element for actuating said switch and operating said valve, heat transfer means for conveying heat from said gases of combustion to the air in the automobile, and means responsive to excessive heat conditions in said heat transfer system to close said valve and open said switch.

6. For use in conjunction with an automobile having an internal combustion engine including an intake manifold and a carburetor, a combustion chamber having an inlet and an outlet, means connecting the outlet of said combustion chamber to the intake manifold of the engine to withdraw products of combustion from said

combustion chamber, means connected to the carburetor for supplying a combustible mixture of liquid fuel and air to said combustion chamber, a valve for controlling the flow of the combustible mixture into said combustion chamber, electrical means for igniting the fuel mixture in said combustion chamber, an energizing circuit for said igniting means, said circuit including a switch, a manually operable element for actuating said switch and operating said valve, heat transfer means for conveying heat from said gases of combustion to the air in the automobile, means responsive to excessive heat conditions in said heat transfer system to close said valve and open said switch, and thermostatic switch means responsive to excessively high temperatures in said combustion chamber to open said igniting means energizing circuit.

EDWARD B. GEORGE.
